(57) **CLAIM**

The ornamental design for a nose pad for a head mounted audio-visual display system as shown and described.

DESCRIPTION

FIG. 1 is a front perspective view of a nose pad for a head mounted audio-visual display system showing our design; FIG. 2 is a rear perspective view thereof; FIG. 3 is a rear view thereof; FIG. 4 is a front view thereof; FIG. 5 is a left-side view thereof; FIG. 6 is a right-side view thereof; FIG. 7 is a top view thereof; and, FIG. 8 is a bottom view thereof.

The dash-dot-dash lines shown in the drawings represent the boundary of nose pad for a head mounted audio-visual display system. The dashed lines represent portions of the nose pad for a head mounted audio-visual display system that form no part of the claimed design.

1 Claim, 8 Drawing Sheets
